UNITED STATES PATENT OFFICE

2,603,970

APPARATUS FOR TESTING PROJECTILE
FUSE SAFETY DEVICES

Silas J. Metzler and Robert H. Thayer, Belmont,
Mass., assignors to the United States of Amer-
ica as represented by the Secretary of the Navy

Application April 11, 1949, Serial No. 86,656

15 Claims. (Cl. 73—167)

1

The present invention relates to an apparatus for testing safety devices as employed in conjunction with fuzes and associated controlling means for projectiles.

More specifically the invention relates to the testing of inertia operated safety devices, such as described in the pending application of Philip S. Williams, Serial Number 534,785, filed May 9, 1944, for a Safety Device, wherein said safety devices are designed to interrupt the ignition conveying train between an explosive squib and the booster charge in an auxiliary detonator, thereby serving as a safety means for preventing premature explosion of a projectile carrying said auxiliary detonator while in, or still close to, the barrel of a gun.

The above-mentioned safety device is controlled by the rotational and linear positive accelerations of the projectile when fired from a gun, which accelerations continue from the time the propelling charge is fired until the projectile has traveled slightly beyond the muzzle of the gun to a point where the propelling effect of the blast is lost. The safety device is designed to keep the ignition train of the fuze in an interrupted state, or in its safe or unarmed condition during this period. However, an improperly assembled safety device might operate imperfectly and thus be unsafe, or allow the fuze to become armed prematurely.

Heretofore it has been customary to detect faulty assemblies by testing samples of each production lot by actual firing of a complete fuze. The procedure has been to fire the fuze through a target set up within the intended "safe distance" in front of the gun muzzle, that is, the distance within which it is designed to remain unarmed. If the fuze detonates within this distance, it is an indication that the safety device within the auxiliary detonator has failed and, therefore, was defective.

This method of testing has been used successfully, but it is slow since it requires the installation of a new target for each shot fired. Accordingly, the present process and apparatus have been developed to permit more rapid testing and to eliminate the need for using the complete fuze in performing said tests.

A further object of the present invention is to provide means for testing the complete operation of the safety device of an auxiliary detonator.

An incidental object of the present invention is to provide means for arming fuzes after the projectiles have been fired from the gun.

Other objects and many of the attendant advantages of this invention will be readily appreci-

2

ated as the same becomes understood by reference to the following detailed description when considered in connection with the accompanying drawings, wherein:

5 Fig. 1 is an axial section of a test projectile according to the invention, the incorporated electrical circuit being shown diagrammatically;

10 Fig. 2 is an axial section of the fixed portion of the test equipment, showing the energizing coil mounted on and in front of the gun barrel, a portion of said barrel being broken away to show the test projectile therein;

15 Fig. 3 is a front view of the device illustrated in Fig. 2, with the energizing coil and its protective fairing partially broken away;

Fig. 4 is an elevation, partially in longitudinal section, of an alternate form of energizer, namely, a tubular permanent magnet;

20 Fig. 5 is a diagrammatic view, similar to Fig. 1, but illustrating a modified embodiment of the test projectile capable of testing the safety device of an auxiliary detonator in both armed and unarmed conditions;

25 Figs. 6 and 7 are circuit diagrams illustrating means for utilizing the invention for arming the electrical circuits of projectile fuzes, and

Fig. 8 is a sectional view of a safety gate employed in projectile fuzes, the energizing circuit used for arming said safety gate being shown diagrammatically.

30 Referring first to Fig. 1, a test projectile 10 is shown with the safety device 11 which is to be tested secured in an axial bore in the mounting block 12 at the forward end of a shell body 13, said body being provided with a colored smoke charge 14 in its rear end portion and with smoke exhausting orifices 15. A nonconducting, nonmagnetic nose portion 16 is screwed on the shell body 13 at 17, and contains an iron-cored pick-up coil 18 which is electrically connected by conductors 19 and 20 to an electric detonator 21, said detonator being secured within an axial bore 22 in the mounting block 12 adjacent to, and co-operating with, the safety device 11.

35 The pick-up coil 18 and the detonator 21 are made inoperative during handling by a set-back switch 23 and a centrifugally actuated spin-switch 24, each being of such construction that it will operate by the forces of acceleration due to the firing of the projectile through a gun barrel. Both of said switches 23 and 24 are normally closed, and are shunted across the conductors 19 and 20 by the conductors 25 and 26 respectively. A delayed action igniter 27 is imbedded in the rear end of the smoke charge 14 and extends through the rear wall 28 of the shell body 13.

For additional protection during pre-fire handling the pick-up coil 18 is magnetically shielded by a soft-iron cap 29 provided to fit over the nose portion 16, said cap being removed before the test projectile 10 is placed in the gun.

Referring now to Fig. 2, there is shown a solenoid 30 comprising an insulating form 31, with a winding 32 thereon, and a generally cylindrically-shaped fairing 33, said solenoid being supported at the muzzle of a gun 34 by brackets 35, here shown as welded on said gun near its muzzle. The solenoid 30 is positioned by said brackets to align it coaxially with the gun muzzle 34 and is separated from it by a distance less than that throughout which the safety device 11 is supposed to remain safe or "unarmed." The cylindrically-shaped fairing 33 is preferably fabricated from a nonmagnetic material of such toughness as to make it capable of withstanding the forces produced at the muzzle of the gun by the explosive blast. As best seen in Fig. 3 the inner diameter 36 of the fairing 33 is slightly larger than the inner muzzle diameter of the gun 34 in order to provide free passage of the projectile on firing. The leads 37 and 38 of the winding 32 are connected to a suitable D. C. source such as the battery 39 shown diagrammatically in Fig. 2.

In use, the solenoid 30 is energized by the D. C. source 39, thus establishing a magnetic field. The test projectile 10 is fired from the gun 34 and, while still subject to the positive acceleration of the muzzle blast, passes through the said solenoid. As the test projectile passes through the field of the solenoid 30, a voltage is induced in the pick-up coil 18 in the nose of the projectile 10 and is applied, through the conductors 19 and 20, to the electric detonator 21 to fire the same. The safety switches 23 and 24 in the shunt conductors 25 and 26 are opened simultaneously with the firing of the projectile by the set-back and centrifugal force respectively, of the said projectile.

If the safety device 11 under test is in proper mechanical condition when the detonator 21 is fired, said device will be in an unarmed condition; that is, with its ignition train misaligned so that the blast from the detonator 21 will not be transmitted to the smoke charge 14. If, on the other hand, the safety device is mechanically imperfect, the explosive train through it may not be sufficiently misaligned and on firing the detonator 21 the flame then will carry through to the smoke charge 14, igniting the same, with the resulting smoke signal discharge escaping through the orifices 15 in the shell body 13. The cloud thus formed by this discharge is distinguishable from that of the muzzle blast by its color.

The delayed-action igniter 27, the operation of which is initiated by the flame from the propelling charge of the gun, is provided to cause burning of the smoke charge 14 at a considerable distance from the gun muzzle, this burning being an indication that said charge was ignitable and that either the safety device 11 had remained unarmed, as intended, or the electric detonator 21 had not fired.

Referring now to Fig. 4, illustrating an alternative embodiment of the solenoid described above and shown in Fig. 2, a permanent magnet 40 having the same generally cylindrical shape as the faired solenoid 30 here replaces said solenoid in advance of the muzzle of the gun and is positioned in place and secured in any suitable way, as by welding, by the brackets 41. This magnet acts in the same manner as the solenoid 30 to induce

a voltage in the pick-up coil 18 in the test projectile.

The above-described apparatus provides a test for the safety device 11 in its unarmed condition.

5 To test the device in its armed condition, modified equipment is required and this is shown in Fig. 5. In this apparatus, the mounting block 12 of the embodiment of Fig. 1 is replaced by a holder 42 with an axial chamber 43 in its rear and to house the safety device 11, said holder being pierced by a diagonal bore 44 directed toward, and intersecting, the chamber 43 at its center. A longitudinal bore 45 having a rearwardly constricted portion 46 intersects said diagonal bore 44 near its point of entry into the chamber 43. The forward, or nose, portion of the projectile accommodates the pick-up coil 18', electrically connected by the conductors 19' and 20' to the electric detonator 21' inserted in the forward end of the longitudinal bore 45 of the mounting holder 42.

The coil 18' and the detonator 21' are made inoperative during handling by the set-back switch 23' and the spin switch 24' each operating similarly to those provided in Fig. 1. Both of said switches are shunted across the conductors 19' and 20' by the conductors 25' and 26' respectively. This nose portion also contains a battery 47 connected in series with an inertia-operated, normally open, delayed-action switch 48 by the leads 49 and 50 of an electric detonator 51, said detonator being inserted in the forward end of the diagonal bore 44. As in the embodiment of Fig. 1, a smoke charge 14' is placed in the shell body 13', 30 rearwardly of the holder 42 and cooperating with the chamber 43, said body being also provided with smoke exhausting orifices 15'. The delayed action igniter 27' is imbedded in the rear end of the smoke charge and extends through the rear wall 28'. As in the embodiment of Fig. 1, a soft iron cap 29' is also provided here for protection during pre-fire handling.

In use, the detonator 21' is fired by passage of the shell through the magnetic field at the muzzle 45 of the gun, as previously described, thereby testing the safety device for proper operation in its safe or unarmed position. Explosion of the detonator 21' does not affect the detonator 51 since the constriction 46 in the bore 45 directs the effect of the blast against the safety device 11, the enlarged bore 44, because of its comparatively increased cross-section, nullifying the effect of the back pressure resulting from said explosion.

Set-back, upon firing of the projectile from the gun, initiates operation of the delayed-action switch 48, which then closes the circuit containing the battery 47, the conductors 49 and 50 and the detonator 51, after the shell has traveled somewhat beyond the accelerating influence of the muzzle blast. On closing the said circuit the detonator 51 is thereby exploded, transmitting its blast through the bore 44 to the safety device 11. If when the detonator 51 explodes, the safety device is operating correctly, the latter should be in an armed condition, thereby transmitting the blast through to the smoke charge 14', igniting the same and producing a cloud at a considerable distance from the muzzle of the gun.

On the other hand, if the safety device is not operating correctly, namely, is unarmed when the detonator 51 explodes, the smoke charge will not be ignited. Of course, if the magnetically initiated detonator 21' had prematurely fired the smoke charge 14', due to a faulty safety device, the firing of the second detonator 51 would have

no visible effect upon the projectile. As was the case in the embodiment of Fig. 1, if the safety device remained unarmed during the exploding of both detonators the smoke charge would eventually be ignited by the firing of the delayed action igniter 27.

It may readily be seen that the system above described may also be employed to arm a fuze after its associated projectile has left the muzzle of a gun. Figs. 6 and 7 show possible arrangements of such a device, schematically.

Referring to Fig. 6, an electric fuze circuit includes a battery 52 and conductors 53 and 53a therefrom. Conductors 54 and 55 from a pick-up coil 56, which would be located in the nose of the projectile, are short-circuited by a set-back 57 and a spin-switch 58 shunted across the conductors 54 and 55 by conductors 59 and 60 respectively. The conductors 54 and 55 are connected, at their ends remote from the pick-up coil 56, to a winding 61 of a locking relay 62. This relay includes a movable contact arm 63 and a fixed contact 64 which are introduced into the fuze circuit conductor 53, to maintain this circuit, which is not fully shown, normally open.

Operation of the device described, and shown in Fig. 6, is similar to that of the testing device hereinabove described. Passage of the projectile, incorporating said device, through either the solenoid winding 32 of Fig. 2 or the permanent magnet 40 of Fig. 4 induces a voltage in the pick-up coil 56. This voltage is applied to the winding 61 of the locking relay 62, causing the contact arm 63 to close with the fixed contact 64 and thereby become locked, closing the fuze circuit through the battery 52, thus arming the complementary fuze circuit of the projectile.

Safety during handling is provided, as in the embodiments illustrated in Figs. 1 and 5, by the set-back switch 57 and the spin-switch 58 each of which will independently provide a short-circuit in the pick-up coil circuit until after the firing of the projectile. A soft iron cap similar to the cap 29 should be applied over the nose of the projectile as an additional precaution against premature arming of said projectile.

Another embodiment of a control for an electric fuze having a battery 65 and conductors 66 and 67 therefrom is shown in Fig. 7. In this form the conductors 68 and 69 from the pick-up coil 70 are connected to a squib 71 in a chamber 72 of a mounting block 73. As previously shown and described, a set-back switch 74 and a spin-switch 75 are shunted across the conductors 68 and 69 by the conductors 76 and 77 respectively. A metallic plunger 78 is located in the chamber 72 adjacent to the squib 71. A pair of spaced contacts 79 in line with the chamber 72 and located at the end thereof remote from the squib 71, interrupt the conductor 67 from the battery 65. In use, a current due to the voltage induced in the pick-up coil 70 explodes the squib 71 to drive the plunger 78 up the chamber 72 and between the contacts 79 and thereby locks said plunger to maintain closed the fuze circuit through the battery 65, thereby arming the fuze.

Referring now to Fig. 8 there is shown an embodiment of the invention to be employed in a projectile having a non-electric type fuze. Here is shown a safety gate 80 with its ignition train misaligned, or in an unarmed condition. Movable gates 81 and 81a with an explosive pellet 82 disposed therebetween are located in a chamber 83 between the aligned sections 84 and 85 of said ignition train. The pellet 82 is normally secured

out of alignment with the sections 84 and 85 by action of a conventional detent 86, shown as a spring-pressed ball riding in a circumferential groove in the wall of chamber 83. An electric squib 87, connected to the conductors 88 and 89 from the pick-up coil 90, is installed in the chamber 83 adjacent to the gate 81. For safety a set-back switch 91 and a spin-switch 92, with conductors 93 and 94 respectively, are shunted across the conductors 88 and 89, thus providing a short circuit between the squib 87 and the pick-up coil 90.

Explosion of the squib 87, caused by a current due to the voltage induced in the pick-up coil 90 on passing through the solenoid winding 32 of Fig. 2 or the permanent magnet 40 of Fig. 4 shifts the gate 81 in the chamber 83, overcoming the resistance of the detent 86 to align the pellet 82 with sections 84 and 85 of the explosive train, for completing the same. The gate is held in this position by a second detent 93 similar to that shown at 86. In this position the ignition train is aligned and the projectile is thus armed for detonation.

Obviously many modifications and variations of the present invention are possible in the light of the above teachings. It is therefore to be understood that within the scope of the appended claims the invention may be practiced otherwise than as specifically described.

We claim:

1. In a system for testing inertia-operated safety devices for projectiles, the combination with a gun for test-firing projectiles containing said safety devices, a source of magnetic flux fixed in proximity to the muzzle of the gun, and a projectile to receive the safety device to be tested, a pick-up coil in the projectile, an electric detonator connected to said coil, and a smoke-producing charge, said safety device being located between said detonator and said charge; passage of the projectile through the magnetic flux inducing an electromotive force in the pick-up coil to explode the detonator during positive acceleration of said projectile, and failure of the safety device permitting transmission of the explosion to and ignition of the smoke-producing charge to indicate said failure.

2. In a system for testing inertia-operated safety devices for projectiles, the combination with a gun for test-firing projectiles containing said safety devices, a source of magnetic flux fixed in alignment with and ahead of the muzzle of the gun, a projectile to receive the safety device to be tested, a nonmagnetic, nonconducting nose on the projectile, a pick-up coil in said nose, an electric detonator connected to said coil, and a smoke-producing charge, said safety device being located between said detonator and said charge; passage of the projectile through the magnetic flux inducing an electromotive force in the pick-up coil to explode the detonator during positive acceleration of said projectile, and failure of the safety device permitting transmission of the explosion to and ignition of the smoke-producing charge to indicate said failure.

3. In a system for testing inertia-operated safety devices for projectiles, the combination with a gun for test-firing projectiles containing said safety devices, a source of magnetic flux fixed in alignment with and ahead of the muzzle of the gun, a projectile to receive the safety device to be tested, a nonmagnetic, nonconducting nose on the projectile, a pick-up coil in said nose, an electric detonator connected to said coil, an

inertia-operated setback switch normally short-circuiting the detonator, an inertia-operated spin switch normally short-circuiting the detonator, and a smoke-producing charge, the safety device to be tested being interposed between the detonator and the smoke-producing charge; passage of the projectile through the magnetic flux inducing an electromotive force in the pick-up coil to explode the detonator during positive acceleration of said projectile, and failure of the safety device permitting transmission of the explosion to and ignition of the smoke-producing charge to indicate said failure.

4. In a system for testing inertia-operated safety devices for projectiles, the combination with a gun for test-firing projectiles containing said safety devices, an electrically energized coil fixed in alignment with and ahead of the muzzle of the gun as a source of magnetic flux, a projectile to receive the safety device to be tested, a nonmagnetic, nonconducting nose on the projectile, a pick-up coil in said nose, an electric detonator connected to said coil, an inertia-operated setback switch normally short-circuiting the detonator, an inertia-operated spin switch normally short-circuiting the detonator, and a smoke-producing charge, said safety device being located between said detonator and said charge; passage of the projectile through the magnetic field of the fixed coil inducing an electromotive force in the pick-up coil to explode the detonator during positive acceleration of said projectile, and failure of the safety device permitting transmission of the explosion to and ignition of the smoke-producing charge to indicate said failure.

5. In a system for testing inertia-operated safety devices for projectiles, the combination with a gun for test-firing projectiles containing said safety devices, an annular permanent magnet fixed in alignment with and ahead of the muzzle of the gun, a projectile to receive the safety device to be tested, a nonmagnetic, nonconducting nose on the projectile, a pick-up coil in said nose, an electric detonator connected to said coil, an inertia-operated setback switch normally short-circuiting the detonator, an inertia-operated spin switch normally short-circuiting the detonator, and a smoke-producing charge, the safety device to be tested being interposed between the detonator and the smoke-producing charge; passage of the projectile through the field of the permanent magnet inducing an electromotive force in the pick-up coil to explode the detonator during positive acceleration of said projectile, and failure of the safety device permitting transmission of the explosion to and ignition of the smoke-producing charge to indicate said failure.

6. In a system for testing inertia-operated safety devices for projectiles, the combination with a gun for test-firing projectiles containing said safety devices, a source of magnetic flux fixed in alignment with and ahead of the muzzle of the gun, and including a coil form having an inner diameter greater than the bore of the gun, a coil of wire wound thereon, a faired cylindrical blast-proof housing for the coil form and coil, brackets for mounting the housing and coil on the muzzle of the gun, and a source of D. C. power for energizing the coil.

7. In a system for testing inertia-operated safety devices for projectiles, the combination with a gun for test-firing projectiles containing said safety devices, a source of magnetic flux fixed in alignment with and ahead of the muzzle

of the gun, said source consisting of a cylinder of magnetically retentive material with an inner diameter greater than the bore of the gun and having faired ends to reduce the force of muzzle blast; said cylinder being longitudinally magnetized.

8. In a system for testing inertia-operated safety devices for projectiles, the combination with a gun for test-firing projectiles containing said safety devices, a source of magnetic flux fixed in alignment with and ahead of the muzzle of the gun, a projectile to receive the safety device to be tested, a nonmagnetic, nonconducting nose on the projectile, a pick-up coil in said nose, a first electric detonator connected to said coil, an inertia-operated setback switch normally short-circuiting said first detonator, an inertia-operated spin switch also normally short-circuiting said detonator, a second electric detonator, a battery, a slow-closing, normally open, inertia-operated switch, said battery being connected to said second detonator through said switch, and a smoke-producing charge, the safety device to be tested being interposed between the smoke-producing charge and the first and second detonators; passage of the projectile through the annular source of magnetic flux inducing an electromotive force in the pick-up coil to explode the first detonator during positive acceleration of said projectile, and failure of the safety device permitting transmission of the explosion to and ignition of the smoke-producing charge as indication of said failure, and proper operation of the safety device preventing such transmission and ignition upon explosion of said first detonator and permitting same upon later explosion of the second detonator, proper or improper performance of the safety device being indicated by the position along the trajectory of the shell of the smoke puff produced by ignition of the charge.

9. In a system for testing inertia-operated safety devices for projectiles, the combination with a gun for test-firing projectiles containing said safety devices, a source of magnetic flux fixed in alignment with and ahead of the muzzle of the gun and within the area of positive acceleration of a projectile fired from the gun, and a test projectile including a projectile body, a charge of smoke producing material in a portion of said body, a plurality of sequentially acting detonators in said projectile, a partition between said charge and said detonators, said partition having a passage through which detonation of said detonator is transmitted to said charge, an inertia-operated safety device secured in said passage and operative to close said passage during intervals of positive acceleration of said projectile and to open the passage after cessation of positive acceleration, a pick-up coil carried by said projectile, connections from said coil to one of said detonators, a plurality of safety switches normally closed to short circuit said coil and prevent detonation of said detonators by accidental energization of said coil, one of said safety switches being actuated to open position by positive acceleration of the projectile in a forward direction, another of said safety switches being actuated to open position by rotation of said projectile about its axis, a source of electric energy in said projectile, connections including a normally-open inertia-operated delayed operation switch responsive to positive acceleration to connect said source to the second of said detonators after cessation of positive

acceleration, and a time delay detonator actuated by the application of the propelling flash to said projectile, passage of the projectile through the magnetic flux inducing an electro-motive force in the pickup coil to explode the first detonator during positive acceleration of the projectile, failure of the safety device permitting transmission of the detonation to the charge, and proper operation of said safety device preventing such transmission upon detonation of said first detonator and permitting transmission upon later detonation of the second detonator, proper or improper performance of the safety device being indicated by the position along the trajectory of the projectile of the signal produced by ignition of the charge.

10. A testing system for inertia-operated safety devices for projectiles, comprising a test projectile, a charge of smoke producing material in said projectile, a plurality of detonator devices in said projectile, a partition between said charge and said detonators, said partition having a passage through which detonation of said detonators is transmitted to said charge, an inertia-operated safety device located in said passage and operative to close said passage during intervals of positive acceleration of said projectile and to open the passage after cessation of positive acceleration, a gun for propelling said projectile, a source of magnetic flux fixed adjacent the muzzle of said gun and within the area of positive acceleration of the projectile, a coil carried by said projectile, said coil traversing said magnetic flux to generate a potential in said coil to detonate the first of said detonator devices during positive acceleration of said projectile whereby failure of said safety device transmits the detonation to said charge, a second source of electric energy in said projectile, and an inertia-operated normally open delayed-action switch connecting said second source to detonate the second of said detonators after cessation of positive acceleration of said projectile whereby normal operation of said safety device transmits said detonation to said charge.

11. A testing system for inertia-operated safety devices for projectiles, comprising a test projectile, a charge of smoke producing material in said projectile, a detonator device in said projectile, a passage between said detonator and said charge, a safety device for test being secured in said passage and operative, during positive acceleration of said projectile in a forward direction, to close said passage, a gun for propelling said projectile, a source of magnetic flux fixed adjacent the muzzle of said gun and within the area of positive acceleration of the projectile, a coil carried by said projectile, said coil traversing said magnetic flux to generate a potential in said coil to detonate said detonator device during positive acceleration of said projectile whereby failure of said safety device transmits the detonation to said charge.

12. A testing system for inertia-operated safety devices for projectiles, comprising a test projectile, a charge of smoke producing material in said projectile, a plurality of detonator devices in said projectile, a channel conducting said detonation to said charge for igniting the same, a safety device for test located in said channel and operative to close said channel during positive acceleration of said projectile and to open said passage after cessation of positive acceleration, a gun for propelling said projectile, a source of magnetic flux fixed adjacent the muzzle of

said gun and within the area of positive acceleration of the projectile, a coil carried by said projectile, said coil traversing said magnetic flux to generate a potential in said coil to detonate the first of said detonator devices during positive acceleration whereby failure of said safety device transmits the detonation of said first detonator to said charge, a second source of electric energy in said projectile and an inertia-operated normally open delayed action switch connecting said second source to detonate the second of said detonators after cessation of positive acceleration of said projectile whereby normal operation of said safety device transmits said detonation to said charge, and a delayed action detonator testing said charge upon failure of said first or second detonators to detonate said charge.

13. A test projectile for testing an inertia-operated safety device, comprising a projectile body, a charge of smoke producing material in a portion of said body, a test detonator in said projectile, a partition between said charge and said detonator, said partition having a passage through which detonation of said detonator is transmitted to ignite said charge, an inertia-operated safety device in said passage and operative to close said passage during intervals of positive acceleration of said projectile and to open the passage after cessation of positive acceleration, a pick-up coil carried by said projectile, connections from said coil to said detonator, a plurality of safety switches normally closed to short circuit said coil and prevent detonation of said detonator by accidental energization of said coil, one of said safety switches being actuated to open position by positive acceleration of the projectile in a forward direction, another of said safety switches being actuated to open position by rotation of said projectile about its axis.

14. A test projectile for testing an inertia-operated safety device, comprising a projectile body, a charge of smoke producing material in a portion of said body, a plurality of detonators in said projectile, a partition between said charge and said detonators, said partition having a passage through which detonation of said detonators is transmitted to said charge, an inertia-operated safety device in said passage and operative to close said passage during intervals of positive acceleration of said projectile and to open the passage after cessation of positive acceleration, a pick-up coil carried by said projectile, connections from said coil to one of said detonators, a plurality of safety switches normally closed to short circuit said coil and prevent detonation of said detonator by accidental energization of said coil, one of said safety switches being actuated to open position by positive acceleration of the projectile in a forward direction, another of said safety switches being actuated to open position by rotation of said projectile about its axis, a source of electric energy in said projectile, connections including a normally open inertia-operated delayed-action switch responsive to positive acceleration to connect said source to another of said detonators after cessation of positive acceleration.

15. A test projectile for testing an inertia-operated safety device comprising a projectile body, a charge of smoke producing material in a portion of said body, a plurality of sequentially acting detonators in said projectile, a partition between said charge and said detonator, said partition having a passage through which detonation of said detonator is transmitted to said

11

charge, an inertia-operated safety device secured in said passage and operative to close said passage during intervals of positive acceleration of said projectile and to open the passage after cessation of positive acceleration, a pick-up coil carried by said projectile, connections from said coil to one of said detonators, a plurality of safety switches normally closed to short circuit said coil and prevent detonation of said detonators by accidental energization of said coil, one of said safety switches being actuated to open position by positive acceleration of the projectile in a forward direction, another of said safety switches being actuated to open position by rotation of said projectile about its axis, a source of electric energy in said projectile, connections including a normally open inertia-operated delayed operation switch responsive to positive acceleration to con-

5

nect said source to the second of said detonators after cessation of positive acceleration, and a time delay detonator actuated by the application of the propelling flash to said projectile.
